[57] CLAIM

The ornamental design for a stem for an article of glassware, as shown and described.

DESCRIPTION

FIG. 1 is a front elevational view of the present design;

FIG. 2 is a left side elevational view thereof;

FIG. 3 is a right side elevational view thereof;

FIG. 4 is a rear elevational view thereof;

FIG. 5 is a top view thereof; and,

FIG. 6 is a bottom view thereof.

The broken line showing of the bowl in FIG. 1 is illustrative of environmental structure only and forms no part of the claimed design.
